G. H. ANTHONY.
TIE AND RAIL FASTENER.
APPLICATION FILED APR. 20, 1921.

1,384,006.

Patented July 5, 1921.

George H. Anthony,

Attorney

UNITED STATES PATENT OFFICE.

GEORGE H. ANTHONY, OF SYKESVILLE, PENNSYLVANIA.

TIE AND RAIL-FASTENER.

1,384,006.

Specification of Letters Patent.

Patented July 5, 1921.

Application filed April 20, 1921. Serial No. 462,850.

To all whom it may concern:

Be it known that I, GEORGE H. ANTHONY, a citizen of the United States, residing at Sykesville, in the county of Jefferson and 5 State of Pennsylvania, have invented certain new and useful Improvements in Tie and Rail-Fasteners, of which the following is a specification, reference being had to the accompanying drawings.

- 10 The purpose of the present invention involves the provision of a metallic tie particularly constructed of steel and provided with pockets for the reception of rail fasteners automatically locking into engagement with the rails, so that the weight of 15 the rails upon certain of the fasteners causes a coöperation between the fasteners and insures a gripping action on the rails to hold them securely in position.
- 20 Another purpose embodies the provision of a tie and rail fastener of the present character, wherein spikes, nuts and bolts and fish plates are entirely eliminated, and yet the rail may be held securely and firmly in 25 position and connected to the tie, said fastenings of the rails on certain of the ties, particularly those where the joint of the rails occurs being provided with means to engage the adjacent ends of two rails, so 30 connecting them as to prevent creeping of the rails, and retaining them securely and firmly connected to the tie.

A further purpose is to provide a rail fastening at the joint of two adjacent rails, so 35 constructed and connected as to permit expansion and contraction of the rails relatively to each other.

A still further purpose is to provide a tie having a pocket or cavity for the reception 40 of a pivoted rail fastener, which normally assumes a position with its rail engaging jaw to one side of the pivot of the fastener and out of contact with the rail, so that upon inserting a second gravity actuated rail 45 fastener, it contacts with the first fastening or fastener and forces it in contact with the rail. The second fastener coöperates with one wall of the pocket and with the first fastening, so that the two fastenings may 50 have firm gripping actions on the rail, holding and clamping the same in position on the tie.

While the design and construction at present illustrated and set forth is deemed preferable, it is obvious that as a result of a re-

duction of the invention to a more practical form for commercial purposes, the invention may be susceptible of changes, and the right to these changes is claimed, provided they are comprehended within the scope of 60 what is claimed.

The invention comprises further features and combination of parts, as will be hereinafter set forth, shown in the drawings and claimed.

In the drawings:—

Figure 1 is a longitudinal sectional view through a tie of the character herein shown including the improved rail fastenings applied and constructed in accordance with the 70 invention.

Fig. 2 is a plan view of the tie and rail fastening.

Fig. 3 is a sectional view through one end of the tie, showing the fastening which is 75 disclosed in Fig. 1, but simply illustrating the rail in the act of gravity actuating one of the fastenings, so that it may cause the operation of another fastening, in order to insure a gripping action of the fastenings 80 upon the rail.

Fig. 4 is a top plan view of a tie, wherein in one end thereof is enlarged, also including a pocket, for the reception of the rail fastenings, which are designed for the purpose of and provided with means for connecting the adjoining ends of two rails, thereby adapting the tie for use where the joints are formed in the rails.

Fig. 5 is a sectional view on line 5—5 90 of Fig. 4.

Referring to the drawings, 1 designates a metallic railway tie preferably constructed of steel, though it may be constructed of any other suitable metal or material, and 95 which comprises a base 2 upwardly from which a plurality of flanges 3 extend. These flanges 3 extend longitudinally of the tie, it being noted that there are preferably three flanges on the tie between the rails, 100 though it is obvious that any number of flanges or strengthening webs may be used. Connecting the flanges which are adjacent the longitudinal edges of the tie are transverse webs 4. The webs 4 are spaced apart, 105 thereby causing to be formed pockets or recesses 5 for the reception of the rail fasteners 6 and 7. The rail fasteners 6 are fulcrumed in the pockets 5 upon the transverse pins 8, though it is obvious that bolts 110

may be employed instead of the pins, or any suitable means (not shown) may be applied to the pins for preventing their displacement. The fasteners 6 when disengaged from the rails assume positions as shown in Fig. 3. In fact the fasteners 6 are so constructed that their weight supports them with their rail engaging jaws assuming positions extending vertically. In fact the fasteners 6 are cut away as shown, and are weighted as shown at 9, so that when the rail is detached, the edges 10 of the fasteners will assume substantially horizontal positions. It is obvious that when the rails are disengaged from the tie, and the fasteners 7 entirely out of engagement with the pockets or recesses, the rail gripping jaws 11 will assume positions extending substantially vertically, with their edges 12 in contact with certain of the transverse ribs 4, thereby acting to limit the fasteners 6 substantially in positions shown in Fig. 3.

When fastening rails 13 in position, their bases are first engaged with the recesses 14 of the rail fasteners 7. These fasteners are gravity actuated, and their edge portions 15 are designed to engage and bear against certain of the flanges 4, thereby bracing or reinforcing the fasteners 7 in place. The recesses 14 are of contours conforming to the shape of the bases of the rails. The beveled or angle edges 16 of the fasteners 7 bear or cam upon the angle edges 17 of the fasteners 6. The weight of the rails 13 and the gravity actuated fasteners 7 will cause the fasteners 6 to rock upon their fulcrum pins 8, and cause the edges 11 of the fasteners 6 to overlie the bases of the rails, and grip against the upper surface of the rails, and in close position to the webs of the rails. The weight of the rails upon the fasteners 7 causes them to bear upon and rock the fasteners 6 in close locking positions with the rails. In fact the greater the pressure on the rails and the fasteners 7, the greater the gripping action will be exercised upon the rails. This is due to the fact that the edge portions 16 of the fasteners 7 will engage and cam against the edge portions 10 of the fasteners 6, thereby throwing the rail clamping or gripping jaws 11 in close position to the webs and the bases of the rails. It is obvious that owing to the constant pressure of the rails, and the constant tension of the jaws, the tighter the jaws will engage the rails.

Referring to Figs. 4 and 5 it will be noted that one end of the tie is wider, with an intermediate rib 3^a at the end of the tie corresponding to the intermediate rib 3 of the central portion of the tie. Also the pockets or recesses 5 are larger, consequently the fasteners which are received in the pockets are larger. In fact the fasteners 7 of Fig. 4 are large enough to lap the adja-

cent ends of the rails 13, a distance to overlie at least two of the usual bolt openings 19 of the webs of the rails. The jaw 20 of the fastener 7 on the left hand side of Fig. 4 is provided with a plurality of lugs 21. The lugs 21 are tapered, in order to guide them into the openings 19 of the web of the rail. The openings 19 are slightly elongated with the length of the rail, and the tapered lugs 21 are of such size as to fit more or less loosely in the openings 19, so as to permit of expansion and contraction of the rails relatively to each other. By this construction the fasteners hold the rails in position, yet at the same time permit movement of the rails longitudinally, due to the expansion and contraction.

The recesses between the ends of the outer flanges 3 have their bottoms inclined, in order to drain off the water and the sleet during cold weather. In Fig. 5 the rail fasteners 6 and 7 are shown in locking positions with the rails, the lugs being in engagement with the bolt openings or holes in the web of the rail.

Referring to the drawing, it will be noted that the central portion of the tie is provided with a plurality of ribs, for instance about three in number, and the bottoms of the spaces between these ribs are inclined toward their centers 22, and adjacent the centers 22 drain openings 23 are provided, for the purpose of draining off the water and sleet as it may collect.

The bottoms of the recesses or pockets 5 are inclined toward their centers, which are provided with openings 24, by which the rain, melted sleet and snow are drained off.

The invention having been set forth, what is claimed as being useful is:

1. The combination with a tie having a pocket, a rail, a fulcrumed rail fastener mounted in the pocket, a gravity actuated rail fastener engageable with the rail and penetratable into the pocket and into operative engagement with the first fastener, thereby causing both fasteners to grip and reinforce the rail in position toward the tie.

2. In a device of the character and for the purpose indicated, a tie having a pocket, a rail, and gravity actuated fasteners mounted in the pocket, one operating the other, to securely grip the rail and forcing the same toward the tie.

3. In a device of the character and for the purpose indicated, a tie provided with a pocket, a rail, gravity actuated fasteners mounted in the pocket, one being guided by the wall of the pocket and having a camming engagement with the other, to insure a constant bearing action of the fasteners on the rail, to secure the rail in place adjacent the tie.

4. In a device of the character and for the purpose indicated, a tie provided with a

5 pocket, a rail, a pair of gravity actuated rail fasteners, one fulcrumed in the pocket, the other slidably engaging in the pocket and having one face bearing against the wall of the pocket and having a camming engagement with the fulcrumed fastener, to insure a firm gripping action upon the rail to force the same toward the tie.

10 6. In a device of the character and for the purpose indicated, a tie provided with a pocket, a rail, a pair of gravity actuated rail fasteners, one fulcrumed in the pocket, the other slidably engaging the wall of the pocket and provided with a camming engagement with the fulcrumed fastener, to insure a firm gripping action upon the rail to force the same toward the tie, one of said fasteners having a plurality of tapered lugs to coöperate with the usual bolt openings of 15 the webs of the rails, thereby holding two adjacent rails in position but permitting of expansion and contraction.

20 7. In a device of the character and for the purpose indicated, a tie provided with pockets, rails resting on the tie transversely of the pockets, a pair of gravity actuated coöperatively engaging fasteners, one fulcrumed in each pocket, the other slidable in each pocket, operative engagements between

the fasteners, to insure a firm gripping action of the fasteners upon the rails. 30

8. In a device of the character and for the purpose indicated, a tie provided with pockets, rails resting on the tie transversely of the pockets, a pair of gravity actuated coöperatively engaging fasteners, one fulcrumed in each pocket, the other slidable in each pocket, operative engagements between the fasteners, to insure a firm gripping action of the fasteners upon the rails, and 35 means carried by one of the fasteners operatively engaging the adjoining ends of the rails, to connect and permit of expansion and contraction. 40

9. In a device of the character and for the purpose indicated, a tie provided with a pocket, adjoining rail ends engaging over the pocket, of coöperative gravity actuated fasteners operatively mounted in the pocket for gripping the adjoining ends of the rails, 45 means on one of the fasteners operatively engaging with the webs of the adjoining ends of the rails for holding them together and permitting of expansion and contraction. 50

10. In testimony whereof I hereunto affix my 55 signature.

GEORGE H. ANTHONY.
